UNITED STATES PATENT OFFICE

JEAN LEYCURAS, OF PARIS, FRANCE.

HEEL FOR BOOTS AND SHOES.

SPECIFICATION forming part of Letters Patent No. 235,262, dated December 7, 1880.

Application filed June 3, 1880. (No model.) Patented in England March 7, 1878.

To all whom it may concern:

Be it known that I, JEAN LEYCURAS, of Paris, France, have invented a new and useful Improvement in Heels for Boots and Shoes; and I do hereby declare that the following is a full, clear, and exact description of the same.

The object of my invention is to provide an improved heel for shoes, provided with improved means for mounting them upon the shoe, in order that increased solidity and greater rapidity of manufacture may be obtained, and whereby nails, screws, and threads are completely masked, and the said nails driven into the heel in such manner that they cannot wound the feet.

My invention consists in the construction and combination of parts hereinafter described, whereby the upper of the boot or shoe is secured by nails which are driven from the outside, and whose heads are masked or concealed by an overlapping piece.

I show in the annexed drawings specimens of a heel provided with groove or recess according to my invention.

Figures 1, 2, 3, 4, and 5 show a side view of a heel having groove or indentation round its periphery; and Figs. 6, 7, 8, 9, 10, 11, and 12 represent different modes of mounting which can be applied to the same.

Referring to Figs. 6 and 7, the letter *a* indicates upper part of the envelope of the heel applied in the groove, and *b* is part of the vamp turned back. *c* is the lining, and *d* counterpart arranged like the lining. *e* indicates a brad or screw driven into the groove to secure the envelope, lining, counterpart, and the vamp upon the heel by a single instrumentality. After the brad has been inserted the vamp *b* is raised, so as to mask the brad, as in Fig. 7.

In Figs. 8 and 9 the vamp is not shown turned back; but a little band, *f*, of leather is applied upon the bottom of the groove, and extends beyond the heel a sufficient distance, Fig. 8, so that it may be bent back above the vamp *b* and hide the nail *e*. The exterior part of this band *f*, having been raised, is glued upon the vamp *b* and smoothed down with an iron

in such manner that one cannot see any break 50 of continuity.

In Fig. 10 the band *f* is replaced by an exterior prolongation of the vamp *b* beyond the line in which the brad or screw is placed. This prolongation *f* of the vamp is pressed 55 back to mask the attaching or mode of fixing, and is glued and ironed down, as has been described above, to render the joint imperceptible.

To mask the heads of the nails or their 60 equivalent the leather of the vamp is notched obliquely at the place where the nail has to be driven; and the little tongue of leather thus formed is fastened down by glue, so that it shall conceal the nail.

Fig. 12 shows the vamp thus cut or notched for the same purpose. A band of sheet-iron might be used for locking all the thicknesses of leather in the groove, and it might be masked either by the vamp or by the envelope turned 70 back.

Figs. 13, 14, and 15 represent a heel in which the groove is made annularly in its upper face. The envelope *a*, the vamp *b*, the counterpart *c*, and the lining *d* are drawn back and 75 fixed in the bottom of such annular groove by the nails *e* or their equivalent. The vamp need not be turned back upon the heel to apply the nails.

Fig. 16 represents a transverse section of 80 a heel with groove round the periphery and undercut above. All the modes of mounting indicated for heels with grooves without undercutting are applicable in this case. The bottom of the groove is pierced at intervals, 85 and the holes which traverse all the thickness of the rim open into the undercut portion, and the pieces can be attached together by needle-work, as well as by nails or screws. The undercutting could be filled by cork or any 90 other filling.

Figs. 17 and 18 represent a heel, *a*, of which the upper part, above the groove, is boxed in with an iron plate, *b*, of which the edges are bent up all around the heel and descend to the 95 bottom of the groove. The part of the iron turned up could be covered with a piece of leather, that can be fixed with a few brads or

screws, whose heads are submerged in the thickness of the leather in the manner described above. This mounting has the advantage of permitting the taking off of the heel and of replacing it easily.

- I have represented in Fig. 19 a grooveless heel, *a*, having an iron rim, *f*, which is provided with an offset forming a groove. The bottom of the offset or groove is at about the level of 10 the upper face of the heel proper, and the vertical part of the rim *f* is pierced with holes *t*, to allow attachment of the leather by means of stitches. The iron is attached to the hinder part of the heel by means of feet *p* and of pins 15 *g*. The replacement of the heel will therefore be easy. It suffices to undo the envelope to raise it and withdraw the pins, and to push the heel from the rear to the front, so that it will escape, leaving all the other parts in place.
- 20 I have represented in Figs. 21, 22, 23, 24 a heel applicable to sandals. These heels have grooves in but one portion of their upper circumference to receive the vamp, which ought not to extend to the rear of the shoe.
- 25 Fig. 21 shows a heel-block in side view. Fig. 22 shows it in transverse section, the plane of section being across the groove. Fig. 23 is a longitudinal section, the plane of which does not cut the groove. *b* is the vamp turned back; 30 *c*, the external part of the vamp bent back upon the heel; *d*, attachment of the vamp and envelope in the groove. *e* is the first sole. *f* is a brad or screw fixing the first sole *e* to the vamp above the heel and to the rear part of the 35 envelope *a* and the first sole *e*.

A last specimen is shown in Fig. 20. The groove of the heel is garnished with a leather, *c*, which projects to a small extent beyond the upper part of the heel.

The mounting can be effected in nailing and 40 screwing the envelope *a* under and with the leather, and in sewing on the upper edge of the leather, and to its interior the vamp *b*, the counterpart *d*, the lining *e*, and the first sole *s*. The heads of the brads which fix the leather of attachment can be hid by making the envelope *a* extend beyond the leather of attachment for 45 a convenient distance, in order that when bent back it may hide completely the leather of attachment. It is then glued and ironed down. 50 In all these modes of mounting the first sole could be bent into the groove and fixed with the other leathers, or else nailed or screwed upon the upper face of the heel. The counterpart and the lining are sewed together after 55 they are mounted upon the heel.

What I claim as new is—

In a boot or shoe, the combination of the heel provided with a circumferential groove with the upper-leather secured at its edge in 60 the said groove by nails driven from the outside thereof, and an overlapping edge or strip of leather, arranged, as described, to be turned up over and mask the nail-heads, substantially as described.

JEAN LEYCURAS.
